NAPPING OR FELT CONDITIONING APPARATUS

Application filed May 22, 1931. Serial No. 539,180.

The invention relates in general to apparatus for producing or renovating nap on fabrics, and more particularly to apparatus for reconditioning the felts of paper making machines. A principal object is to provide novel and improved means for cleaning, combing or clearing lint, pulp particles, etc. from the conditioning roll.

Appliances of this general character are intended to recondition or maintain in proper condition the felt which receives the paper pulp and transfers it from one stage to another of the paper or pulp making machine. Reconditioning of the felt which is in the form of a continuous belt or conveyor, is effected by applying to its surface properly pointed teeth carried by a rotary drum or cylinder, so that the teeth restore the matted nap of the felt to proper condition and also remove particles of pulp, which tend to fill or clog the felt. This roll is traversed laterally of the felt while the latter moves continuously about its pulley, so that the entire surface of the felt is treated in the reconditioning process.

A principal feature of the present invention is the provision in connection with the reconditioning roll and its traversing means, of combing and stripping means cooperating with the teeth or bristles of the roll to strip or clear therefrom particles of lint, paper pulp, etc. which are taken up by the conditioning roll in operation, thus keeping the roll in proper condition for proper action upon the felt. The comb has teeth normally entering between the teeth or bristles of the conditioning roll, and the stripper is provided with teeth located between the comb teeth; provision is made for intermittently or periodically moving the comb away from the zone of the bristles of the conditioning roll, and in such movement the stripper cooperates with the comb to discharge from it the material which it has removed from the bristles. This periodical withdrawal of the comb is effected automatically by the lateral transversing movement of the conditioning apparatus.

An important feature is the mounting or arrangement of the conditioning apparatus,

in a paper making machine or the like, below the lower stretch of the felt apron, in such manner that lint, pulp fragments, etc. removed from the felt are discharged downward away from it, and do not tend to fall back and remain upon the felt, as occurs when conditioning apparatus is arranged above an active stretch of the felt.

The characteristics and advantages of the invention are further sufficiently explained in connection with the following detail description of the accompanying drawing, which shows one preferred embodiment. After considering this example, skilled persons will understand that many changes may be made without departing from the principles disclosed; and I contemplate the employment of any structures that are properly within the scope of the appended claims.

Fig. 1 is a vertical section of conditioning apparatus embodying the invention in one form.

Fig. 2 is a bottom plan, with some parts in section.

Fig. 3 is a sectional detail at 3—3 of Fig. 1.

In Figs. 1 and 2, 1 is the lower stretch of a felt, or felt apron, of a paper making machine, of the character briefly referred to above and more particularly described hereinafter. This apron passes about pulleys of which one pulley 2 is shown, revolvably supported in a frame structure of the machine. One of the frame uprights 3 is illustrated. The conditioning apparatus is arranged below the lower stretch 1 of the felt. This apparatus, except for improved features presently described, comprises a supporting beam 5 which is itself supported on the frame uprights 3. The web of beam 5 is horizontal and its flanges 6 are vertically disposed, to constitute rails for the carriage wheels or rolls. The carriage 7 of the conditioning mechanism is of inverted U form, straddling the supporting beam 5, and has flanged rolls 8 on upper and lower shafts 9 and 10, respectively engaging the upper and lower portions of the beam flanges 6 to guide the carriage for reciprocation transversely of the machine and of the felt 1.

The carriage 7 has arms 11 provided with 100

bearings 12 in which a shaft 13 is revolvably supported. This shaft carries a conditioning roll 14 which is provided with wire bristles 15 having pointed hooked ends to engage the felt and raise or restore the nap thereon and at the same time remove particles of the paper pulp. The roll shaft 13 has at its ends pulleys 17 connected by belts 18 to pulleys 19 which are revolvably mounted in bearings 20 on the carriage. A clutch rod or shaft 21 is arranged to reciprocate in the pulleys 19, and carries clutch members 22 which are pinned or otherwise connected to the clutch rod. The teeth of these clutch members cooperate with complementary teeth 23 of ratchet form on the respective pulleys 19. The clutch rod 21 supports spacing sleeves 24, 25, and a worm sleeve 26 located between the spacing sleeves. This worm sleeve has a slot 27, and a key or pin 28 fixed in the clutch rod engages in the slot to rotarily drive the worm sleeve and also to permit the shifting movement of the rod. The worm sleeve has a worm 26a engaging a small worm gear 29 on the upper end of a vertical shaft 30 mounted in a bearing 31 in the upper portion of the carriage. Fixed on the lower end of this shaft is a spur pinion 32 engaging a rack 33 secured to the web of the supporting frame 5 so that when the worm is rotated in either direction shaft 30 is rotated, and by engagement of pinion 32 with the rack 33 the carriage is traversed on the supporting beam in a corresponding direction. One of the belts 18 is "open" and the other is "crossed", as clearly indicated in Figure 2 so that as the conditioning roll 14 is rotated in the direction of the arrow Fig. 1 by tractive force of the belt 1 in a direction also indicated by an adjacent arrow, one of the pulleys 19 is driven in one direction and the other is driven in the opposite direction. Axial shifting of the clutch rod 21 is therefore effective to traverse the carriage in either direction and so to move the conditioning roll back and forth laterally across the under surface of the felt 1, as the felt continuously advances in the indicated direction. The traversing movement of the carriage is thus effected by tractive engagement of the conditioning roll with the felt.

Shifting of the clutch rod is accomplished by engagement with stops 35 adjustably supported at opposite ends of the supporting beam 5, only one of these stops being shown, in Fig. 2. Cushioning springs 36 are provided on the ends of the clutch rod 21, extending beyond the rod ends, and it is the ends of the springs which actually engage the stops, thus providing a cushioned, automatically effected shifting movement of the rod and reversal of carriage travel without undesirable shock or jar.

The invention includes as a principal feature a comb 40, Fig. 1, comprising a base or supporting strip 41 provided with combing

teeth 42 having their end portions slightly curved as at 43, and usually pointed. These teeth are so arranged on the supporting strip that they are located between the annular rows of napping bristles 15 as well shown in Figs. 1 and 2. The comb strip is supported at its ends by arms 44, secured to a rod or shaft 45, which is mounted to oscillate in bearing sleeves 46 which are secured on or formed integrally with the carriage arms 11. On each end of the comb shaft 45 is an arm 48, each carrying a cam follower 49, which desirably is, as shown, of ball form, and may be mounted to rotate on the end of its arm 48.

Each of these followers cooperates with a cam, or cam channel 50, defined by upper and lower parallel or other suitably related flanges 51 and 52 on a plate 53, which is secured to one of the flanges 6 of the supporting beam 5. Only one of these cam plates is shown in the drawing, but of course, there is another one at the other end of the supporting beam to cooperate with the other follower 49.

To clean the comb, a stripper is provided which may be in the form of a metal strip 60 having its ends secured to the carriage arms 11 and cut to provide stripping teeth 61 located between the comb teeth 42, as clearly shown in Figs. 1 and 3.

As the conditioning roll 14 rotates in contact with the felt, its bristles take up lint and pulp fragments, and these are removed by the comb teeth 42. It will be observed that the direction of rotation of the conditioning roll in relation to the comb teeth is such that by the slight frictional engagement of the bristles with the comb teeth the comb tends normally to be held in active position as shown in Fig. 1, and also tends to remain in this position by gravity and by the weight of arms 48 and their cam followers 49, while the carriage is at intermediate points of its lateral travel.

As the carriage approaches one end of its travel, the cam follower 49 at the end of shaft 45 corresponding to the direction in which the carriage is moving, enters the corresponding cam channel 50 and the follower is deflected upward by the lower flange 52, thus oscillating the shaft 45 and moving the comb teeth in an arcuate path away from the bristles 15, and at the same time the comb teeth wipe across the stripping teeth 61, which remove from the comb the fibrous or other material which it has removed from the bristles, thus keeping the comb practically clear and clean and in proper condition to keep the bristles in clear and clean condition, since the stripping or clearing action of the comb occurs at each end of the carriage travel. On return movement, that is, after reversal of carriage movement, the cam follower 49 is forced downward by the upper cam flange 51, thus positively returning the comb to active position in relation to the stripper and with

its teeth located between the bristles of the conditioning roll; and the comb remains in this position during the lateral traversing of the carriage until it reaches the other end of such traversing movement, whereupon the comb is again withdrawn, and so on.

It will now be understood that this combing and stripping mechanism may be applied to other fabric conditioning apparatus or to apparatus of the present general type or class used for other purposes, as, for example, in vacuum cleaners having napping, pile raising or renovating means to act on carpets, rugs or the like while the vacuum suction is applied, substantially as disclosed in my co-pending application, Serial No. 272,967, filed

April 26, 1928 for apparatus for cleaning and conditioning fabrics; and the present application is in part a continuation of that application.

I claim:

1. Fabric conditioning apparatus comprising a conditioning roll having bristles engaging the fabric, and a comb having teeth engaging between annular rows of the bristles and acting to clear therefrom lint and other material taken up by the bristles, periodically effective means for limiting the extent of travel of said roll and means for removing the comb from the zone of the bristles, said removing means being effective at the respective limits of the travel of said conditioning roll.

2. Fabric conditioning apparatus comprising a conditioning roll having bristles engaging the fabric, and a comb having teeth engaging between annular rows of the bristles and acting to clear therefrom lint and other material taken up by the bristles, and means for periodically removing the comb from the zone of the bristles, and a stripper acting in such movement of the comb to remove the stated materials from the comb.

3. Felt conditioning apparatus for purposes described, in combination with the lower stretch of a traveling felt, said apparatus comprising a conditioning roll arranged below and in contact with the under surface of said lower stretch of the felt, and means for traversing the conditioning roll laterally in relation to the felt, and a comb for clearing from the roll fibrous matter removed from the felt and means for periodically retracting the comb.

4. Felt conditioning apparatus for purposes described, in combination with the lower stretch of a traveling felt, said apparatus comprising a conditioning roll arranged below and in contact with the under surface of said lower stretch of the felt, and means for traversing the conditioning roll laterally in relation to the felt, and a comb for clearing from the roll fibrous matter removed from the belt, and a stripper cooperating with the comb.

5. Fabric conditioning apparatus comprising a reciprocating carriage, a conditioning roll revolvably mounted in the carriage and having bristles to cooperate with a fabric, a comb having teeth interspaced with the bristles, and means for periodically retracting the comb teeth from the bristle zone.

6. Fabric conditioning apparatus comprising a reciprocating carriage, a conditioning roll revolvably mounted in the carriage and having bristles to cooperate with a fabric, a comb having teeth interspaced with the bristles, and means acting at ends of the carriage travel to retract the comb from the bristles.

7. Fabric conditioning apparatus comprising a reciprocating carriage, a conditioning roll revolvably mounted in the carriage and having bristles to cooperate with a fabric, a comb having teeth interspaced with the bristles, and means acting at ends of the carriage travel to retract the comb from the bristles, and a stripper on the carriage having teeth interspaced with the comb teeth and acting when the comb is retracted from the bristles to clear fibrous material from the comb.

8. Fabric conditioning apparatus comprising a reciprocating carriage, a conditioning roll revolvably mounted in the carriage and having bristles to cooperate with a fabric, a comb having teeth interspaced with the bristles, and means acting at ends of the carriage travel to retract the comb from the bristles, said means comprising cams in fixed position and cam followers connected to the comb.

9. Fabric conditioning apparatus comprising a reciprocating carriage, a conditioning roll revolvably mounted in the carriage and having bristles to cooperate with a fabric, means actuated by rotation of the conditioning roll to traverse the carriage, a comb having teeth interspaced with the bristles, and means for periodically retracting the comb teeth from the bristle zone.

10. Fabric conditioning apparatus comprising a reciprocating carriage, a conditioning roll revolvably mounted in the carriage and having bristles to cooperate with a fabric, means actuated by rotation of the conditioning roll to traverse the carriage, a comb having teeth interspaced with the bristles, and means acting at ends of the carriage travel to retract the comb from the bristles.

11. Felt conditioning apparatus for purposes described, in combination with the lower stretch of a traveling felt, said apparatus comprising a conditioning roll arranged below and in contact with the under surface of said lower stretch of the felt, means for traversing the conditioning roll laterally in relation to the felt, a comb for clearing from the roll fibrous matter removed from the felt, a stripper, and means effective at predeter-

5 mined locations of the lateral travel of said conditioning roll for effecting relative movement between said comb and said stripper, to thereby clear said comb of lint and other material.

12. Felt conditioning apparatus for purposes described, in combination with the lower stretch of a traveling felt, said apparatus comprising a conditioning roll arranged below and in contact with the under surface of said lower stretch of the felt, means for traversing the conditioning roll laterally in relation to the felt, a comb for clearing from the fibrous matter removed from the felt and means for periodically retracting the comb, a stripper, and cam operated means effective at predetermined locations of lateral travel of said conditioning roll for displacing said comb relative to said stripper to thereby clear the comb relative to said stripper to thereby clear the comb of lint and other material.

13. Fabric conditioning apparatus comprising a reciprocating carriage, a conditioning roll revolvably mounted in the carriage and having bristles to cooperate with a fabric, a comb having teeth interspaced with the bristles, means for reciprocating said carriage in the direction of the axis of said roll, and cam operated means acting at ends of the reciprocating travel of said carriage to retract the comb from the bristles.

14. Fabric conditioning apparatus comprising a reciprocating carriage, a conditioning roll revolvably mounted in the carriage and having bristles to cooperate with a fabric, means actuated by rotation of the conditioning roll to traverse the carriage in a direction of the axis of said conditioning roll, a comb having teeth interspaced with the bristles, and means effective at predetermined locations of the path of axial travel of the conditioning roll for retracting the comb teeth from the bristle zone.

15. Felt conditioning apparatus for purposes described, in combination with a stretch of a travelling felt, said apparatus comprising a conditioning roll provided with bristles, a comb engaging the bristles of said conditioning roll, means for moving the comb in a direction away from the bristles, and stripper means acting to clear the comb upon such movement of said comb.

16. Felt conditioning apparatus for purposes described, in combination with a lower stretching a travelling felt, said apparatus comprising a conditioning roll provided with bristles, a comb engaging the bristles of said conditioning roll, means for moving the comb in a direction away from the bristles, and stripper means acting to clear the comb upon such movement of said comb.

In testimony whereof I have signed this specification this 15th day of April, 1931.

MORTIMER F. FLYNN.
